Attorney

UNITED STATES PATENT OFFICE.

CHARLES L. LAWTON, OF HANCOCK, MICHIGAN.

GOLF-CLUB HEAD.

Application filed May 3, 1920. Serial No. 378,573.

To all whom it may concern:

Be it known that I, CHARLES L. LAWTON, a citizen of the United States, and residing at Hancock, in the county of Houghton and 5 State of Michigan, have invented a new and Improved Golf-Club Head, of which the following is a specification.

This invention relates to the construction of the heads of golf clubs, and its object is 10 to so position weights relative to the bottom faces of the heads that the action on the ball of the blow delivered by the club may be closely predetermined.

When a golf club such as a brassie or 15 driver having a head of wood has a weight secured below the central horizontal plane of the head or "underslung," so that the effective momentum shall be along the bottom face of the club and below the point of 20 contact with the ball when the club is properly used, this weight not only assists in the "follow-through" of the stroke, but also assists in keeping the face of the club in its normal vertical position at the 25 moment it contacts with the ball. The effect of an "underslung" club is to cause the ball to back-spin or rotate backward and so cause it to carry farther, but to roll a comparatively short distance when it strikes the 30 ground, due to the backward rotation. This "underslung" feature is therefore valuable for playing on wet grounds where the roll of the ball cannot be relied upon.

When a weight is mounted above the mid- 35 dle of the club head or "overslung" the result is a club which causes the ball to over-spin or rotate forward. While this somewhat reduces the flight of the ball, it con- 40 duces to long and fast rolling on hard dry grounds so that the total distance gained is greater than when the underslung club is employed.

This invention consists in the details of construction illustrated in the accompanying 45 drawing and particularly pointed out in the claims.

In the drawings, Fig. 1 is a face elevation, Fig. 2 is a bottom view, and Fig. 3 an end view of the head of an underslung golf club 50 in which a weight is mounted so as to embody my present invention. Fig. 4 is a section on the line 4—4 of Fig. 1. Fig. 5 is a plan of an over-slung golf club embodying the present invention. Fig. 6 is a section on the 55 line 6—6 of Fig. 5.

Similar reference characters refer to like parts throughout the several views.

The golf clubs whose heads are shown in Figs. 1 to 4 of the drawing are of wood and are attached to shafts or handles, which 60 are not shown, in any desired manner. I have shown a front plate 1 of metal, preferably brass, secured to the head 2 by the screws 3, and this plate is connected to the bottom plate 4 or integral therewith, the 65 bottom plate being of any desired size and form and preferably united to the head by the screws 5.

Integral with this bottom plate is a boss or weight 6 whose dimensions are shown in 70 cross section in Fig. 4 and indicated by the dotted lines 7, 8 and 10 in Fig. 2. A bolt 9 screws into a properly threaded hole in this boss 6 and its head 11 engages the bearing plate 12. This not only assists in uniting 75 the plate 4 and its boss to the head 2, but also serves to prevent the head from splitting. By thus fastening the weight, a cross stress is placed upon the screws 5 by this bolt 9 and these screws are thereby prevented 80 from becoming loose.

The boss 6 increases in vertical thickness and decreases in horizontal width toward the back of the club, and as a result there is a minimum torsion on the shaft or handle of 85 the club when the ball is hit by the toe or heel of the face of the club, and the tendency to slice or hook the ball is greatly lessened.

In the brassie shown in Figs. 5 and 6, the front plate is omitted and a narrow bottom 90 plate 15 takes the place of the bottom plate 4 of Fig. 2, although a piece of metal of any other desired shape may be employed. A weight 16 is secured to the top of the head 17 by means of the screws 18 and it tapers 95 toward the front face of the club. A diagonal bolt 19 again screws into a properly threaded hole in this weight and its head engages the bearing plate 20. This bolt again not only assists in uniting the weight to the 100 head and prevents the head from splitting but it serves to prevent the screws 18 from becoming loose.

It will be understood that the sizes and proportions of the various parts may be va- 105 ried by those skilled in the art without departing from the spirit of my invention as set forth in the following claims.

I claim:-

1. A golf club having a head of wood pro- 110

vided with a bottom plate of metal having a boss extending up into a recess in the bottom of the head, the upper surface of the boss inclining downwardly toward the face 5 of the head and the boss decreasing in width toward the back of the club, a bolt extending through the head from the rear downwardly and engaging in a hole in said boss, and screws to secure the bottom plate and 10 boss in position, said screws being stressed laterally by said bolt.

2. A golf club having a head of wood and a metal weight embedded in the club and spaced vertically from the middle of the 15 head of the club, said weight tapering to-

ward the front of the head in a vertical plane and toward the rear of the club in a horizontal plane, and a bolt extending diagonally from the rear of the head and engaging in a hole in said weight.

20

3. A golf club having a head of wood and a metal weight embedded therein between the front and rear thereof and tapering toward the front of the club, screws to secure the weight in position, and a bolt extending 25 at an angle to the line of the screws from the rear side of the head into engagement with said weight.

CHARLES L. LAWTON.
